UNITED STATES PATENT OFFICE.

NICHOLAS A. BARNELL, OF CLEVELAND, OHIO, ASSIGNOR TO THE P. A. GEIER COMPANY, OF CLEVELAND, OHIO, A CORPORATION OF OHIO.

DESIGN FOR A SUCTION-CLEANER NOZZLE.

Application filed July 22, 1921. Serial No. 486,894. Term of patent 14 years.

To all whom it may concern:

Be it known that I, NICHOLAS A. BARNELL, a citizen of the United States of America, residing at Cleveland, in the county of Cuyahoga and State of Ohio, have invented a new, original, and ornamental Design for Suction-Cleaner Nozzle, of which the following is a specification, reference being had to the accompanying drawing, forming a part thereof.

Figure 1 of said drawing is a view in front elevation of a suction cleaner nozzle, showing my new design, and

Figure 2 shows the same in side elevation.

The design comprises a relatively long, narrow, tapering bottom-member, with slightly recessed ends, which member centrally merges into a graduated uptake and angularly-extending, straight-sided cylindrical body.

I claim:

The ornamental design for a suction cleaner nozzle, as shown.

In testimony whereof I do now affix my signature.

NICHOLAS A. BARNELL.
